Radio Corporation of America, a corporation of Delaware

Application February 27, 1943, Serial No. 477,435

5 Claims. (Cl. 250—13)

The present invention relates to high frequency filter systems for connecting one or more transmitters and receivers to a common antenna system and, furthermore, to such systems for use in pulse transmitting and receiving systems for non-signaling purposes.

An object of the present invention is the provision of a filter system for enabling the selective connection of a transmitter and a receiver to a common antenna system without requiring the use of mechanical switching.

Another object of the present invention is the provision of a filter network, the operating characteristics of which are controlled by the power applied thereto.

A further object of the present invention is the provision of a filter system for pulse transmitting and receiving systems.

Still a further object of the present invention is the provision of an antenna filter system for pulse transmitting and receiving equipment which utilizes no moving parts or mechanical switches for diverting the outgoing and incoming pulses to the appropriate transducer equipment.

The foregoing objects, and others which may appear from the following detailed description, are attained in accordance with the principles of the present invention by providing a filter system between an antenna and receiver and a transmitter, said system utilizing a plurality of resonant structures acting as filter elements. The structures may be empty resonant chambers or cavity resonators, or they may take the form of resonant line filters, and it should be clearly understood that hereafter in referring to resonant structures it is intended to include any and all of the above mentioned types, whether or not actual lumped or distributed circuit elements are employed. The filter elements are so placed and are so connected to the antenna transmitter and receiver through electrical discontinuities that when signaling potentials are applied to the system from the transmitter the electrical discontinuities are caused to break down and become conducting. The filter sections then cause the energy from the transmitter to be conducted to the antenna but prevent its application to the receiver. When the transmitter ceases operation the electrical discontinuities are restored and the signals picked up by the antenna are applied to the receiver. The electrical discontinuities are so placed that no received energy is wasted in the transmitter.

The present invention will be more completely understood by reference to the following detailed description, which is accompanied by a drawing, in which Figure 1 illustrates in partial section an embodiment of the present invention, while Figures 2, 3 and 4 each illustrate modifications thereof. In Figure 1, 10 represents in fragmentary cross-section a portion of a radio transmitter which may be of the magnetron type. This type of transmitter is particularly desirable when operating at ultra high frequencies though, of course, if it is desired to use the present invention with lower frequency waves a transmitter of some more conventional type may be used. Coupled to the transmitter 10 through the intermediary of a coupling loop 14 is one end of a transmission line 11 having an outer shell 13 and a concentrically located inner conductor 12. The other end of transmission line 11 is connected to radiating means, as indicated by the label "To antenna." The inner conductor 12 has an electrical discontinuity 15 therein, the purpose of which will be more fully de-

2

scribed later. On the side of the electrical discontinuity 15, remote from the transmitter 10, is connected a structure resonant to the operating frequency; said structure may be in the form of a hollow closed cylinder or shell 33 having an overall length from one end wall 34 to the other 35 of substantially a half of the operating wavelength. Through wall 34 of the cylinder 33 passes a second transmission line 23 having an outer shell 32 and an inner concentrically arranged conductor 22. The exterior end of transmission line 23 is coupled to a suitable receiver of high frequency energy. The outer conductor 32 of transmission line 23 extends substantially to the middle of cylinder 33 and at that point is connected to the inner conductor 12 of transmission line 11. The inner conductor 22 of the transmission line 23 is carried on as an extension 22' to the wall 35 of cylinder 33 and is separated therefrom only by an electrical discontinuity 25. Electrical discontinuities 15, 25 may be actual breaks in the conductors forming spark gaps or gas discharge tubes may be employed in their place if desired.

In the operation of the structure described, the operation of transmitter 10 causes gap 15 to break down very easily thus energizing the end of the shell 32 of the receiver transmission line 23. The electrical distance from the free end of shell 32 to a point directly opposite, in shell 33 being a half wavelength, the end of shell 32 presents a high impedance to the energy from transmitter 10. Some energy being transferred to conductor 22', gap 25 breaks down and the quarter wave extension 22' also presents a high impedance to the energy at the mouth of shell 32. Thus there is no effective potential difference between the conductors of transmission line 23 and very little energy passes to the receiver. The major portion of the energy from the transmitter therefore passes on along transmission line 11 to the antenna. When the transmitter ceases operation the electrical discontinuities in each of the gaps 15 and 25 are restored. The gaps do not break down when a received signal arrives. The end of extension 22' adjacent wall 35 is thus substantially free. At the mouth of shell 32 the resultant effect is as though the center conductor 22 of transmission line 23 were grounded at the mouth of shell 32. Since the end of shell 32 is free to swing with respect to ground the received energy passes to the receiver. The gap 15 in line 12 from the transmitter blocks the energy from going in that direction.

It will thus be apparent that in operation substantially all of the energy from the transmitter will be applied to the antenna while when the transmitter is not in operation and received signals come from the antenna to the filter network substantially all of the received energy will be applied to the receiver, none being wasted in the transmitter circuits.

The modification of the present invention illustrated in Figure 2 in general operates in the same way as described above with reference to Figure 1. However, instead of, as in Figure 1, providing a series gap 15 in the line to the transmitter 10 in Figure 2 a supplemental trap circuit including shell 43 and central conductor 42 is provided. The central conductor 42 is connected at its other end to the end of shell 43 through a spark gap or other electrical discontinuity 45. It will be noted that the length of conductor 42 is a quarter wavelength at the operating frequency and the length of conductor 12 between the point of connection of conductor 42 and shell 32 is also a quarter wavelength. Now, when transmitter 10 supplies energy to the transmission line 13, gap 45 breaks down thus effectively grounding the conductor 42 at its end to shell 43. It therefore presents at its point of connection to conductor 12 a high impedance to the high frequency energy from transmitter 10 and substantially no energy is lost at that point. The transmitted energy is then fed to the antenna along conductor 12 as described with reference to Figure 1. However, when receiving signals neither gap 35 or gap 45 breaks down. Gap 35 acts in the same way as described before. Gap 45 causes an extremely low impedance to the energy to be presented at the junction of conductor 42 and conductor 12 since conductor

42 is now an open-ended quarter wave conductor. Due to the quarter wavelength spacing between the junction of conductors 42 and 32 with conductor 12 a high impedance is presented at the junction of conductors 12 and 32. Conductor 22 being effectively grounded at the mouth of shell 32 and the said mouth being effectively at high impedance above ground, all of the received energy will be applied to the receiver through transmission line 23. This modification has the advantage over the previously described modification in that none of the spark gaps are required to carry large amounts of current. It is only necessary that they carry sufficient energy to break down the gaps.

The modification in Figure 3 illustrates the use of cavity resonators for providing the switching functions between the transmitter and receiver and antenna. In this modification there is provided a cavity resonator 53 operating as a structure resonant to the desired frequency. The resonator is preferably so dimensioned that the oscillations therewithin are of the lowest mode, that is, with the electric field parallel to the axis and with a transverse circular magnetic field. Here the energy from the transmitter. Breaks down gap 56 and due to the current flow along conductor 12 excites the interior of the cavity to resonance. Conductor 62 from the antenna passing through the cavity 53 and linking the lines of force within the cavity in the same way as conductor 12 picks up the energy from the transmitter and applies it to the antenna. Sufficient energy is picked up by extension 54 by inner conductor 22 of the receiver transmission line so that gap 52 breaks down. Due to conductor 54 within shell 55 being substantially a quarter wave in length, point X on the conductor 54 appears at a very high impedance. Thus substantially no current can flow along conductor 22 and no energy is supplied to the receiver. When the transmitter ceases operation and incoming signals are applied to conductor 62 the interior of cavity 53 is again excited. Due to the fact that gap 56 is now open no current can flow along conductor 12 and no energy is applied to the transmitter. However, gap 52 is also open which causes point X on conductor 54 to appear as a very low impedance. Thus current may flow along conductor 22 and the received energy may be applied to the receiver.

The operation of the modification shown in Figure 4 is the same as that shown in Figure 3, the only substantial distinction being that the transmitter and receiver transmission lines 13 and 23 both enter the cavity 53 from the same side. This is of some convenience in assuring the most direct connections between the filter network, the transmitter, the receiver and the antenna.

While I have illustrated several embodiments of the present invention, it should be clearly understood that it is not limited thereto since many further modifications may be made in the several elements employed and in their arrangement and it is therefore contemplated by the appended claims to cover any such modifications as fall within the spirit and scope of the invention.

I claim:

1. A filter element including a first conductor, a second conductor parallel thereto and of substantially equal length, a third conductor parallel to said first two of one half of the length of each of said two and connected to said first conductor at one end thereof, a two conductor transmission line coupled at an intermediate point to said first conductor and to said third conductor at its free end, a discharge path connecting said first and third conductors at the other end of said first conductor, a transmitter coupled through a discharge path to said

transmission line and receiver means coupled across said second and third conductor.

2. A filter system including a resonant chamber having a pair of opposite walls spaced apart a distance equal to a half of the operating wavelength, a first transmission line having an outer shell and an inner conductor, the outer shell of said transmission line passing through one of the opposing walls of said chamber and extending into said chamber a distance equal to one quarter of the operating wavelength, the inner conductor of said transmission line being coupled to the other of said opposing walls through a discharge path, a second similar transmission line having its inner conductor entering said chamber and connected to the end of the outer shell of said first transmission line, the outer shell of said second transmission line being connected to the casing of said resonant chamber and a source of high frequency energy connected to said second transmission line in said chamber through a second discharge path.

3. A junction between a plurality of transmission lines, one of said lines being associated with a source of high frequency energy, said junction including a chamber resonant to said energy, a conductor of said one transmission line having an electrical discontinuity therein and passing into said chamber, another of said transmission lines having associated therewith a receiver, a conductor of said other transmission line extending into said chamber and coupled thereto through an electrical discontinuity, the extending portion of said conductor having such length that when said discontinuity is closed said other transmission line is not coupled to said chamber, the last of said transmission lines being associated with an antenna and coupled to the interior of said chamber.

4. A junction between a plurality of transmission lines, one of said lines being associated with a source of high frequency energy, said junction including a chamber resonant to said energy, a conductor of said one transmission line having a discharge path therein and passing into said chamber, another of said transmission lines having associated therewith a receiver, a conductor of said other transmission line extending into said chamber and connected thereto through a discharge path, the extending portion of said conductor having a length equal to one quarter of the operating wavelength such that when said discharge path is closed said other transmission line is not coupled to said chamber, the last of said transmission lines being associated with an antenna and coupled to the interior of said chamber.

5. A junction between a plurality of transmission lines, one of said lines being associated with a source of high frequency energy, said junction including a chamber resonant to said energy, a conductor of said one transmission line having a spark gap therein and passing into said chamber, another of said transmission lines having associated therewith a receiver, a conductor of said other transmission line extending into said chamber and connected thereto through a spark gap, the extending portion of said conductor having a length equal to one quarter of the operating wavelength such that when said spark gap is closed said other transmission line is not coupled to said chamber, the last of said transmission lines being associated with an antenna and coupled to the interior of said chamber.
